UNITED STATES PATENT OFFICE.

ALEXANDER Q. NASH, OF KANSAS CITY, MISSOURI.

IGNITION-DETECTOR AND SPARK-INTENSIFIER.

1,338,521.

Specification of Letters Patent. Patented Apr. 27, 1920.

Application filed April 26, 1918. Serial No. 231,030.

To all whom it may concern:

Be it known that I, ALEXANDER Q. NASH, a citizen of the United States, and resident of Kansas City, in the county of Jackson 5 and State of Missouri, have invented certain new and useful Improvements in Ignition - Detectors and Spark - Intensifiers, of which the following is a specification.

The invention relates to apparatus for indicating the condition of the controlling circuits for a gasoline engine. The invention includes a device which is intended to indicate the condition of the circuit and which may perform the functions of a detector, to 15 enable the operator of a gasoline engine to ascertain whether the sparking apparatus is operating properly in all the cylinders; it also operates to perform the function of an intensifier by insuring a sufficiently 20 strong current to produce an effective spark in each cylinder.

The general object of the invention is to produce a simple apparatus for this purpose which will provide a spark gap at 25 which the spark may be observed, in this way indicating whether the current is passing in the controlling circuits. Features of the invention relate to the supporting means for the terminals between which the spark 30 gap is formed and also to the means co-operating therewith to control the flow of the current through the terminals.

In the preferred form of the invention, I employ a freely movable contact which is 35 disposed in the spark gap, and features of the invention relate to the means for holding the terminals in a substantially vertical position so that the supporting surfaces for the movable member will be substantially 40 horizontal.

The invention consists in the general combination of the parts and features to be particularly described hereinafter all of which contribute to produce a simple and efficient 45 ignition detector and spark-intensifier. A preferred embodiment of my invention will be particularly described in the following specification while the broad scope of my invention will be pointed out in the appended 50 claims.

In the drawing,

Figure 1 is a vertical section through apparatus embodying my invention, and including a diagram of the wiring which may 55 be used with the apparatus.

Fig. 2 is a vertical section taken about on the line 2—2 of Fig. 1.

Fig. 3 is a front elevation of the apparatus shown in Fig. 1, upon a reduced scale,

Fig. 4 is a plan of a portion of a bracket 60 which constitutes a feature of the invention, the terminal which is supported by the bracket being indicated in cross section, and

Fig. 5 is a vertical section through the device showing a modified construction for my invention and indicating how it can be applied directly to an ordinary spark-plug.

Referring more particularly to the parts, in carrying out my invention, I provide a plurality of spark tubes 1, 2, 3 and 4, each 70 of which corresponds to one of the cylinders of the engine indicated at 5 (see Figs. 1 and 3). Each engine cylinder carries a spark plug 6 and these spark plugs 6 are wired in parallel, with the different sparkling tubes in series with the plugs. Fig. 1 illustrates the preferred construction of each sparking tube, each of which comprises a short length of a translucent tube 7 which may be of glass, and the ends of this tube 80 are provided with caps 8 and 9 which may be sealed to the tube by means of cement so as to form a hermetically sealed sparking chamber within the tube. These caps are preferably of insulating material, and the lower cap 9 carries a fixed terminal 10 the outer end of which projects from the head 9 and engages a bracket 11. The upper terminal 12 passes into the interior of the tube 7 through the upper cap 8 and engages 90 with an upper terminal bracket 13. These brackets are simply bent pieces of conductive material such as brass, and conductors 14 corresponding to the different plugs 6 are attached respectively under terminal 95 bolts which form binding posts 15. Other conductors 16 from a distributor 17 lead the current to similar bolts forming binding posts 18 which are connected respectively with the brackets 11. A conductor 19 leads 100 the current to the distributor from a battery 20 or other source of current which is grounded or connected to the engine as at 21 so as to form a complete circuit through each detector tube.

The terminals 12 are preferably adjustable, for which purpose they have a screw connection with the cap 8 and pass down into the interior of the tube, the inner end being provided with an enlarged condenser 110

plate or terminal head 22. Each lower terminal 10 is also provided with a condenser plate or terminal head 23, and these terminal heads are disposed apart so as to form 5 a spark gap across which the current must jump when the ignition is operating. In order to maintain the adjacent flat surfaces 24 of these terminal heads in a good clean 10 sparking condition I prefer to provide a freely movable conductive member which may be in the form of a small metal ball 25 of steel or any other suitable conductive 15 material. If the width of the spark gap is properly adjusted by means of the threaded terminals 12, and their co-operating clamping nuts 26, the spark will jump from the ball to the upper terminal head 22 or vice versa, and the ball will jump up and down 20 between the faces of the terminal heads thereby keeping the faces of the heads clean.

It is desirable that the lower surface 24 which supports the ball 25 should be substantially horizontal; in other words, the tube should be held with its axis in a substantially vertical position. As the instrument board of different automobiles may be at different angles, I provide means for adjustably supporting the tubes in a vertical position, whatever may be the relation of 30 the support to them. This means preferably comprises a movable mounting back or "board" 27 to which the brackets 11 and 13 are secured by means of the terminal bolts 18 and 15 respectively, and I prefer to 35 mount the board with the tubes which it carries in a suitable case 28 which may be of simple box form, provided with a front window 29 of glass, the upper edge of the window frame being attached by hinges 30 40 so that the frame can be swung up to give access to the interior of the case. The ends of the back or "board" 27 are provided with studs 31 which project through the side walls 32 of the case and operate as trunnions on which the back may swing. Between the walls 32 and the ends of the back, 45 spring washers 33 are provided, and the outer portions of the bolts 31 are provided with nuts 34 and check nuts 35; from which 50 arrangement evidently the back 27 will be readily adjustable into a vertical plane, even if it should happen that the case 28 is disposed in an inclined position, such as it would have if it is mounted in an inclined instrument board 36.

I provide means for cutting out the detector tubes, if desired, so that the ignition circuit will not pass through them. For this purpose I provide a multiple switch 60 which is preferably mounted on the rear side of the back or board 27. This multiple switch is of very simple form and consists of a lever 37 corresponding to each terminal bolt 15, the heads of which operate 65 as contacts to be engaged by the swinging

ends of the levers. The lower ends of the levers are pivoted on the terminal bolts 18 and the levers are all connected in a parallel position by a drag bar 38 of insulating material which is pivotally attached to them. 70

In order to enable the switch to be operated or "thrown" from the exterior of the case, I provide means for this purpose which consists of a stem 39 which is rotatably mounted in a bracket 40 attached on the forward face of the back 27. The rear portion of this stem extends through the wall and is bent around so as to form an arm 41 the end of which is bent forwardly so as to form a pintle 42. By inspecting Fig. 2, it will be evident that if the stem 39 be rotated in a left hand direction, the arm 41 will swing toward the left and the levers 37 may be moved into engagement with their corresponding contacts 15. Evidently the circuit 80 will then short-circuit through the switch levers 37 and cut out the detector tubes. The stem 39 passes to the exterior of the case through a slot 43 in the forward wall of the case. (See Fig. 3). It is necessary 90 to provide this slot on account of the necessity for tilting the back 27 to enable it to maintain a vertical position, as it may be necessary to attach the case in an inclined position as indicated in Fig. 1. On the 95 outer end of the stem, means is provided such as a thumb head 44 to enable the stem to be rotated from the exterior. The detector tubes are detachably mounted in the brackets 11 and 13. For this purpose the 100 lower end of the terminal 10 projects from the cap 9 and is received in a socket in the form of a small cup shaped depression 45 formed in the bracket 11. The upper bracket 13 is in the form of a plate with a slot 47 105 extending in from its edge, and into the open end of which the terminal 12 may be passed in putting the tube in position. The bracket 13 is also provided with a slight bend or bow 46 on which the nut 26 seats, 110 and as the bracket is of resilient material this bend co-operates with the nut to get the effect of a check nut. In this way the nut 26 not only operates to enable the terminal 12 to be secured in any adjusted position 115 with respect to the terminal head 23, but it will be evident that by loosening it up, the entire tube can be readily disengaged or detached from the back. In doing this the lower bracket 11 which is slightly resilient 120 may be sprung downwardly.

In some cases it may not be desired to mount the tubes within the body of the automobile, in which case they can be attached to the outer ends of the spark plugs. 125 Such an arrangement is shown in Fig. 5 in which 48 indicates the outer end of the spark plug, which is assumed to be in an inclined position. In order to enable my sparking tube to be attached to it and held 130

in a vertical position, I provide a bracket 49, one arm of which is attached to the binding post of the spark plug by the nut 50. The other arm is horizontal and supports the sparking tube 51, in a vertical or upright position. This sparking tube has substantially the same construction as that indicated in Fig. 1, except that the lower terminal 52 seats directly on the horizontal 5 arm of the bracket 49 to which it is secured by a thumb screw 53. This terminal 52 has a circumferential wall 54 within which the lower end of the translucent tube 55 is cemented, the upper end of the tube being cemented in a metal cap 56 through which the adjustable terminal 57 passes downwardly. The lower end of the terminal is formed with a terminal head 58 which cooperates with the part 52 to form a spark 10 gap in which a ball 59 is held. The glass tube 55 is enveloped in a cylindrical casing 60 of hard rubber or similar material, the lower end of which is threaded to the outer side of the wall 54 of the lower terminal or 15 cap 52. The upper end of the tubular casing is formed with an opening which receives a circular boss 61, on the underside of a cap screw 62, which cap screw seats on the upper end of the casing 60. The conductor 63 is secured on the cap screw by a suitable thumb nut 64. The cap screw 62 has a threaded connection with the threads of the terminal 57 and hence operates as a check nut. Diametrically opposite points 20 of the wall of case 60 are provided with sight openings 65 through which the spark gap is visible.

The terminal heads will also operate in the usual manner of condenser plates to 25 build up a difference in the potential at the gap, and as long as the current is able to jump this gap the spark plugs will be assured of a good hot spark.

It is obvious that any number of switch 30 levers 37 and corresponding contacts 15 may be employed, and one pair may be provided for the starting circuit of the engine, in which case my apparatus will indicate the condition of the starting circuit as well as 35 the condition of the ignition circuit.

It will be noted that as the terminals 10 and 12 are connected in the regular or normal ignition circuit the gap between them has the effect of intensifying the ignition 40 spark. That is to say, if the current is strong enough to jump the gap between the heads 22 and 23 a good ignition spark will be formed in the cylinder; in addition to this the heads operate as condenser plates 45 which operate to increase the electricity that will collect in the ball, thereby increasing the activity of the jumping movements of the ball. In this way the terminal heads 50 tend to increase the efficiency of the ball 55 in keeping their surfaces clean.

It is understood that the embodiment of the invention described herein is only one of the many embodiments my invention may take, and I do not wish to be limited in the practice of my invention nor in my claims, 70 to the particular embodiment set forth.

What I claim is:—

1. An ignition detector and spark-intensifier comprising the combination of a translucent tube, insulating caps mounted in the 75 ends of the tubes, a terminal extending inwardly into the interior of the tube from each of the caps, said terminals being connected in series with the spark plug of the engine and disposed apart to form a spark 80 gap in the ignition circuit visible through the tube, and a freely movable metallic ball held by said tube between said terminals operating to intensify the spark at the spark plug and as a detector to indicate whether 85 a spark is being formed at the spark plug.

2. An ignition detector and spark intensifier comprising the combination of a translucent tube, insulating caps mounted in the 90 ends of the tube, a terminal extending inwardly into the interior of the tube from each of the caps, said terminals being connected in series with the spark plug of the engine, condenser plates carried by said terminals and disposed apart to form a spark 95 gap in the ignition circuit visible through the tube, a freely movable metallic ball held by said tube between said condenser plates operating to maintain the faces of the condenser plates in a clean condition, and means 100 for adjusting the distance between the condenser plates.

3. An ignition detector and spark-intensifier, comprising the combination of a translucent tube, caps mounted in the ends thereof, a terminal extending inwardly into the interior of said tube from each of said caps, a terminal head carried by the end of each of said terminals within said tube, said terminal heads being disposed apart to form a 105 spark gap visible through said tube, a freely movable conductive body confined in the spark gap by said tube and said terminal heads, a support for said parts, and means for adjustably holding said support in a 110 substantially upright position.

4. An ignition detector and spark-intensifier for a gasoline engine, comprising the 115 combination of a translucent tube corresponding to each cylinder of the engine, said tubes having caps in the ends thereof, a terminal extending inwardly into the interior of each tube at each end, the adjacent ends of said terminals of each tube coöoperating to 120 form a spark gap visible through the tube, a freely movable conductive body confined in each spark gap by its terminals and tube, and a support carrying all of said tubes, and 125 adjustably mounted within said case to en- 130

- able said tubes to be held with their axes in a substantially vertical position.
5. An ignition detector and spark-intensifier, for a gasoline engine, comprising the combination of an adjustable supporting back, brackets disposed in pairs mounted on the face of said back, each pair of brackets being connected in a circuit to a corresponding cylinder of the engine, a translucent tube with caps at the ends thereof, removably mounted between each pair of brackets, each of said tubes having a terminal passing into the interior thereof from each end of the tube and engaging its adjacent bracket, the adjacent ends of said terminals coöperating to form a spark gap within each tube visible through the tube, and a freely movable ball of conductive material confined in the spark-gap between the terminals of each tube.
- 10 6. An ignition detector and spark-intensifier, for a gasoline engine, comprising the combination of an adjustable supporting back, brackets disposed in pairs mounted on the face of said back, each pair of brackets being connected in a circuit to a corresponding cylinder, of the engine, a translucent tube with caps at the ends thereof, removably mounted between each pair of brackets, each of said tubes having a terminal passing into the interior thereof from each end of the tube and engaging its adjacent bracket, the adjacent ends of said terminals coöperating to form a spark gap within each tube visible through the tube, a freely movable ball of conductive material confined in the spark-gap between the terminals of each tube, and a multiple cut-out switch for cutting out each pair of terminals from their corresponding circuit.
- 15 7. An ignition detector and spark-intensifier for the gasoline engine of an automobile comprising the combination of a case to be mounted in the automobile body, an adjustable supporting back within said case having means for holding the same in a substantially vertical plane, a plurality of translucent tubes supported on said back, each tube corresponding to a cylinder of the engine and having a pair of terminals projecting into the tube from the ends thereof connected to the ignition circuit for the corresponding cylinder of the engine, each pair of terminals within each tube being disposed apart and coöperating to form a spark gap, a metallic ball confined in each spark gap, a cut-out switch carried by said supporting back for cutting out said terminals, said case having a slot on its forward side and said switch having an operating stem extending through said slot, said stem having a thumb head on the exterior of said case for operating the switch.
- 20 8. An ignition detector and spark-intensifier for the gasoline engine of an automobile body, comprising the combination of a case to be mounted in the automobile body, an adjustable supporting back within said case having means for holding the same in a substantially vertical plane, a plurality of translucent tubes supported on said back, each tube corresponding to a cylinder of the engine and having a pair of terminals projecting into the tube from the ends thereof connected to the ignition circuit for the corresponding cylinder of the engine, each pair of terminals within each tube being disposed apart and coöperating to form a spark gap, a metallic ball confined in each spark gap, a cut-out switch carried by said supporting back for cutting out said terminals, said case having a slot on its forward side and said switch having an operating stem extending through said slot, said stem having a thumb head on the exterior of said case for operating the switch.
- 25 9. In apparatus of the class described, the combination of a supporting back, a bracket attached thereto and having an arm with a slot, projecting from said bracket, a coöperating bracket opposite said first named bracket, also carried by said supporting back, said coöperating bracket having a depression therein, a tube having a terminal in each end, one of said terminals projecting at one end of said tube to be received in said depression, the other end of said terminals being received in said slot and having a nut for clamping the same to the bracket, said slotted bracket having a bend at said nut and being of resilient material to coöperate with said nut in securing the terminal thereto.
- 30 10. In an apparatus of the class described, the combination of a supporting back, a bracket attached thereto, and having an arm with a slot extending in from the edge of said arm, a coöperating bracket opposite said first named bracket also carried by said supporting back, said coöperating bracket having a socket, a tube having a terminal in each end, one of said terminals projecting at one end of said tube to be received in said socket, the other end of said terminals being received in said slot, said slot being disposed so as to permit the entrance of the terminal into the same by the lateral movement of that terminal when the opposite terminal is placed in said socket, and a nut on the terminal adjacent said slotted arm for clamping the terminal thereto.
